DESIGN FOR A SCARF BLOUSE

Joseph F. Berlinger, New York, N. Y.

Application November 17, 1937, Serial No. 72,943

Term of patent 3½ years

To all whom it may concern:

Be it known that I, Joseph F. Berlinger, a citizen of the United States of America, residing in New York city, in the Borough of Manhattan, county and State of New York, have invented a new, original, and ornamental Design for a Scarf Blouse, of which the following is a specification, reference being had to the accompanying drawing, forming part thereof, wherein,

I claim:

The ornamental design for a scarf blouse, substantially as shown.

JOSEPH F. BERLINGER.
